UNITED STATES PATENT OFFICE.

TAUBE DAVIS, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed August 11, 1926. Serial No. 18,696. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the skirt is distinguished by a central box plait at the front with a group of knife plaits on each side, all of the plaits having an ornamental stitching at the top for giving a flat effect. The dress is also distinguished by the ornamental neck

piece on the tunic or jumper, the horizontally spaced ridges and the ornamental belt at the lower part of the tunic. The tunic is distinguished in addition by an ornamental vestee with a series of round buttons and co-operating loops, the vestee matching in color and general design with the ornamental cuff positioned at the lower end of each sleeve.

The figure is a front view of a dress, showing my new design.

I claim:

The ornamental design for a dress, substantially as shown and described.

TAUBE DAVIS.
